Primary Examiner — Jeffrey D Asch*Assistant Examiner* — Sanjeev Paul(74) *Attorney, Agent, or Firm* — Joe Zheng(57) **CLAIM**

I claim the ornamental design for a handset, as shown and described.

DESCRIPTION

FIG. 1 is a front perspective view of a handset incorporating my new design;

FIG. 2 is a rear perspective view of the handset;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The two broken line circles at the rear represent the bounds of the claim, while the broken lines showing "Snail" are directed to environment that is superimposed on a continuous claimed surface; the broken lines form no part of the claimed design. "Snail" shown in the drawing disclosure is a registered trademark of Suzhou Snail Electronic Co. Ltd., Suzhou CHINA.
